UNITED STATES PATENT OFFICE.

ROBERT EUGENE DOWNS, OF VINTON, IOWA, ASSIGNOR OF ONE-HALF TO
GEORGE M. HOYT, OF SAME PLACE.

BORING-MACHINE.

SPECIFICATION forming part of Letters Patent No. 549,849, dated November 12, 1895.

Application filed July 12, 1895. Serial No. 555,709. (No model.)

To all whom it may concern:

Be it known that I, ROBERT EUGENE DOWNS, a citizen of the United States, residing at Vinton, in the county of Benton and State of Iowa, 5 have invented certain new and useful Improvements in Boring-Machines; and I do hereby declare the following to be a full, clear, and exact description of the invention, such as will enable others skilled in the art to 10 which it appertains to make and use the same.

My invention relates to improvements in boring-machines; and the main object of my invention is the provision of a boring-machine which will bore horizontally, vertically, or at 15 an incline and which can be quickly adjusted to the character of work to be accomplished, and which machine will be simple, inexpensive, and thoroughly practical in construction.

To attain the desired objects the invention 20 consists of a boring-machine embodying novel features of construction and combination of parts substantially as disclosed herein.

In order that the details of construction and operation of my machine may be readily understood and its numerous advantages be 25 fully appreciated, I would call attention to the drawings, which illustrate a boring-machine constructed according to my invention.

Figure 1 represents a perspective view of 30 my improved boring-machine with the parts adjusted for boring horizontally. Fig. 2 represents a similar view with the parts in the position they assume when boring vertically, and Fig. 3 represents a vertical sectional view.

Referring by numerals to the drawings, the 35 numeral 1 designates a hollow standard or tube having at its upper end a set-screw 2, and to the lower end thereof is pivoted the plate 3, formed with barbs or points 4, adapted to bite or engage the suitable surface to support the tube in any desired position, as will be readily understood. To the lower end of 40 said tube opposite the support-plate is secured the bracket 5, having a stud 6, upon which is mounted the wheel 7, having the gear-teeth 8 on its inner face and the crank 9 on its outer face or rim. The said teeth engage with the pinion 10, secured to the lower end of the rod 45 11, bearing in the bracket 12, and having the shouldered portion 13 for holding said rod in

the proper position in said bracket, and adjustably fitted on said rod is the tube or sleeve 14, secured in place by means of brackets 15 and 15', and to the upper end of said sleeve 55 or tube is connected the auger or bit 16. From this construction it will be seen that rotation of the driving-wheel revolves the rod and the sleeve fitted thereon and imparts this action to the auger or bit carried by said sleeve, and 60 it will also be noticed that said sleeve is adjustable on said rod, for a purpose which will presently appear. To the upper end of the sleeve is secured, a beveled pinion 17, which engages with the horizontally-disposed bevelled pinion 18, carrying the bit or auger 19, mounted in the rod 20, which fits in the hollow standard 1 and is adjustable therein and can be held at any adjustment by means of the set-screw secured in the said hollow standard. 70

When it is desired to bore a horizontal opening, the rod is adjusted in the hollow standard and the sleeve which fits on the driving-rod is correspondingly adjusted by the adjustment of said rod, and when motion is imparted 75 through the driving gear-wheels the beveled pinion on the sleeve operates the beveled pinion carrying the horizontally-disposed auger, as will be readily understood.

In boring a vertical opening I provide a device for feeding the bit upward as it enters the wood. This consists of the spring 21, which bears at one end upon the hollow standards 1 and at its other end upon the collar 22, mounted on the rod 20, said collar having the adjusting-screw 23, which engages said rod, and by this construction it will be seen that the tension of the spring bearing upon the collar moves the rod, which moves the vertically-disposed bit or auger upward, as is evident, the 80 screw 2 in the hollow standard being released from engagement with the rod 20 to permit the spring to move said rod 20 upward as the bit or auger enters the wood.

This boring-machine may be used in many 95 situations but is specially useful for electricians, as it can be adjusted to any position and will bore openings in any directions desired, and as it is of simple and inexpensive construction it is thoroughly practical and useful. 100

I claim—

1. In a boring machine, the combination of

the support, the standard adjustably connected therewith, the driving mechanism carried by the standard and horizontally and vertically disposed bits operated by the driving mechanism.

2. In a boring machine the combination of a support, a hollow standard or sleeve connected therewith, the driving mechanism carried by the standard and an adjustable boring mechanism consisting of vertically and horizontally disposed bits or augers operated by said driving mechanism.

3. In a boring machine, the combination of the hollow standard carrying the driving mechanism, the rod fitting in the hollow standard and carrying the horizontally disposed bit or auger, the spring for moving the

rod vertically and mechanism for operating said bit or auger.

4. In a boring machine, the combination of the hollow standard, the rod adjustable therein, the spring for moving said rod vertically, the sleeve connected with said rod and carrying the bit or auger, and the driving rod fitting in said sleeve and carrying the pinion engaging the driving wheel carried by the standard.

In testimony whereof I affix my signature in presence of two witnesses.

ROBERT EUGENE DOWNS.
